STRETCHER AND GUIDER

Robert Daniel Tackaberry, Lewiston, Maine

Application May 28, 1934, Serial No. 727,938

17 Claims. (Cl. 26—67)

This invention relates to an improved guider and stretcher for cloth or other materials which in varying operations need to be guided and stretched particularly during travel of the same over rolls.

The problem of providing a simple and efficient device that would stretch and straighten the material to secure an even and straight flow of the same to the final rolling mechanism has had many supposed solutions. Many of these employed suitably spaced pairs of rolls to grip the margins of the material; and the correction of undesired lateral movement of the material was secured by separating one pair of rolls, which left the tension of the other pair of rolls to check and correct the lateral movement. To accomplish this, electrical means were commonly used. With all these devices, there were weaknesses represented generally by expensive and complicated constructions, frequent breakdowns, especially at the hands of unskilled or careless labor, and inability to handle materials at relatively high speeds.

For that reason, my solution of the problem is largely one of simplification which provides at the same time a more sensitive yet more durable device.

In accordance with my invention, I utilize the unbalanced forces resulting as the cloth develops undesired lateral movement to effect equal, though opposite, pivoting movement of the marginal rolls simultaneously to cause the angles of the rolls to the cloth to be varied so that the pull of the marginal rolls is varied to effect an increased pull on the side from which the material is retreating immediately straightening the flow of the material.

In the drawings I have illustrated and in the specification described a practical embodiment of my invention. Throughout the specification and drawings, like reference numerals are employed to indicate corresponding parts, and in the drawings:

Fig. 1 is a front view of my guider and stretcher.

Fig. 2 is an end elevation of the same.

Fig. 3 is a plan view of Fig. 1.

Fig. 4 shows my device viewed along the lines 4—4 of Fig. 3, and

Fig. 5 is a fragmentary view of the feeler arm.

I provide a suitable frame consisting of fixed uprights F and vertically spaced cross members F¹ and F². A pair of rotatable shafts 1 and 2 are journaled in bearings 1¹ and 2¹ in the up-

rights F and are centrally mounted in a common bearing block 3.

Slidably mounted on the cross members F¹ and F² are guide supports 4 and 5, each of which is provided with an internally threaded bracket 6 which is movable on a feed screw 7 having reverse threads so that the supports 4 and 5 may be simultaneously adjusted for various widths of cloth by turning the hand wheel 7^a.

The supports 4 and 5 carry fixed yokes 8 and 9 which are bolted or otherwise rigidly secured to their respective supports at 8¹ and 9¹. Within each of the yokes 8 and 9 are pivotally supported on the shafts 16 and 16^a opposed cradles 10 and 11, in which cradles are mounted for free rotation the edge-gripping rolls 12 and 13 which grasp the edges of the material to be fed vertically therethrough, although, of course, my device may be positioned to receive any flow of material.

The tension of the rolls 12 and 13 on the cloth may be varied by means of adjustment screws 14 which bear against springs 15 supported by the shafts 16 on which the cradles 13 are pivoted. In order that the rolls may be disengaged to facilitate the feeding of the cloth therethrough, a manually operable control arm 17 fulcrumed as at 18 is pivoted to the shaft 16.

Spliced to the shafts 1 and 2 are members 19, the position of which is controlled by a bridge 19^a connected to the brackets 6 by the rods 21 so that the members 19 will always maintain the same relative position to the supports 4 and 5. Each of the members 19 is provided with a fixed arm 22 which is operatively connected at 24 to the rack 23. (See Fig. 2.)

The rack 23 meshes with a gear 25 which through the shaft 27, turns gears 28 and 29 in mesh with quadrants 30 and 31 on the cradles 10 and 11 (see Fig. 3) so that rotation of the shafts 1 and 2 will result in a rotation of the cradles 10 and 11 effective to produce tugs in opposite directions on the margins of the material.

To detect lateral movement of the cloth, I provide a feeler arm or governor 32 which extends transversely of the flow of the cloth. This arm 32 is provided with rods 33^a and 33^b between which and a centre portion 33^c the cloth or other material passes, as is shown in Fig. 4. The feeler arm shown, while representative of the principle of my invention, may obviously be variously formed as, for example, to impart to it desirable guiding qualities.

The feeler arm 32 is carried by a shaft 34 mounted in the centrally positioned upright 35

rigidly supported on the cross members F^1 and F^2 , which has an overhang 35^1 between which and the upright 35 a balance 41 is carried on the shaft 34 . By means of the arcuate aperture 41^a in the balance 41 with the stud 42 on the upright 35 the balance serves to limit the tilting movement of the arm 32 in either direction.

A centrally pivoted lever or balance beam 36 is mounted on the shaft 34 from each end of which depends a connecting rod 39 . The shafts 1 and 2 are provided with members 37 which carry horizontal arms 38 pivotally connected at 40 to the connecting rods 39 on the ends of the beam 36 . (See Fig. 4.)

15. I may provide a connection from the feed screw 7 or handwheel 7^a to the main rollers (not shown) so that on adjustment of these main rollers for the proper width of cloth, the marginal guiding and stretching rolls will be properly positioned 20 at the same time. I also contemplate the use, in some installations, of a second similar device as that described to ensure sufficient power to guide and stretch properly the heavier materials.

In the operation of my apparatus, the frames 25 4 and 5 with the attached yokes 8 and 9 , carrying the pivoted cradles 10 and 11 , in which rotate the cloth edge gripping rolls 12 and 13 , are adjusted through the feed screw 7 for the width of cloth to be guided. The cloth is then run 30 between the rods 33^a and 33^b and over the member 33^c of the feeler arm 32 . The control arm or lever 17 is depressed to permit the cloth to enter between the rolls 12 and 13 and the tension of the rolls is adjusted by means of the screws 35 14 . As the marginal rolls 12 and 13 are always equi-distant from the center, the forces exerted by the flow of the cloth will be evenly distributed over the feeler arm 32 which will continue to balance perfectly so long as the cloth is running 40 perfectly straight. As the cloth runs through, however, it will invariably tend to have an undesirable lateral movement. This movement will cause the sensitive feeler arm 32 to tilt since it will be thrown out of balance, and this will cause 45 one connecting rod 39 to be raised and the other to be lowered. Through the connections 37 and 38 the shafts 1 and 2 will be rotated in opposite directions. This movement will cause the racks 50 23 to actuate the gears 25 and 26 , which in turn will actuate the gears 28 and 29 in mesh with the quadrants 30 and 31 on each cradle 12 and 13 and thereby turn the same on their pivots 16 and 16^a . This movement of the cradles results in the simultaneous, equal but opposite, pivoting of each pair of rolls. I preferably have 55 my rolls exert a slight pull on each margin of the cloth by positioning them at an angle of less than 90° to the margin of the cloth in straight flow. The pull on either margin will obviously be increased by making the angle of the roll to the margin more acute. In accordance with my invention, the feeler arm 32 is tilted by the forces exerted by incorrect flow and the pull on the side from which the material has retreated is increased. Simultaneously, the pull on the other side is decreased so that lateral deviations of 60 the material are immediately corrected.

Various modifications in the construction of my guider and stretcher may obviously be resorted to without departing from the spirit of my invention if within the limits of the appended claims.

What I therefore claim and desire to secure by Letters Patent is:

75. 1. In a device of the class described, a frame

including a cross member, a cradle pivotally and slidably connected with each end of said cross member, a pair of contacting rolls mounted for free rotation in each of said cradles and being so positioned as to constitute each pair of rolls 5 a grip for a margin of the material, a feeler arm pivotally connected with said cross member between said pair of rolls and adapted to receive the cloth in desired flow as a balanced load and to be tilted by the forces exerted by unbalanced 10 loads, and means operatively connected with said arm to produce simultaneous equal movements of said cradles whereby undesired lateral movement of the material is immediately corrected.

2. In a device of the class described, a frame 15 including a cross member, a cradle pivotally and slidably connected with each end of said cross member, means for synchronously adjusting the lateral position of each cradle to receive materials of different widths, a pair of rolls mounted 20 for free rotation in each of said cradles and being positioned to constitute each pair of rolls a grip for a margin of the material, a feeler arm pivotally connected with said cross member and adapted to receive the cloth in desired flow 25 as a balanced load, and means connected with said arm to produce simultaneous opposite equal movements of said cradles whereby undesired lateral movement of the material is immediately corrected.

3. In a device of the class described, a frame including a cross member, a pair of cradles pivotally and slidably connected with each end of said cross member, means for synchronously adjusting the lateral position of each pair of cradles to receive 35 materials of different widths, a pair of rolls mounted for free rotation in each of said cradles and being so positioned as to constitute each pair of rolls a grip for a margin of the material, means to separate said rolls to admit the material, a 40 feeler arm pivotally connected with said cross member between said pair of rolls and adapted to be tilted by the forces exerted by uneven flow of the cloth, and means operatively connected with said arm to produce simultaneous opposite equal 45 movements of said cradles whereby undesired lateral movement of the material is immediately corrected.

4. In a device of the class described, a frame including a cross member, a pair of cradles pivotally and slidably mounted on each end of said cross member, means for synchronously adjusting the lateral position of each pair of cradles to receive materials of different widths, a pair of rolls mounted for free rotation in each of said cradles and being so positioned as to constitute each pair of rolls a grip for the margin of the material, a centrally pivoted feeler arm adapted to balance during desired flow of the cloth, and means connected with said arm to produce simultaneous opposite equal movements of said cradles whereby undesired lateral movement of the material is immediately corrected.

5. In a device of the class described, a frame including a cross member, a pair of cradles pivotally and slidably mounted on each end of said cross member, a pair of rolls mounted for free rotation in each of said cradles and being so positioned to constitute each pair of rolls a grip for the margin of the material, a centrally pivoted 70 feeler arm responsive to the forces exerted by the flow of the cloth and a balance for said arm, stops with said balance to prevent excessive movement of said arm, and means connected with said arm to produce simultaneous opposite equal pivotal 75

movements of said cradles whereby undesired lateral movement of the material is immediately corrected.

6. A guiding and straightening mechanism for materials of the class described, comprising a frame including uprights and cross members, spaced material guide supports slidably adjustable on said cross members, a yoke rigidly carried by each of said supports, a cradle pivoted in each of said yokes, a pair of material edge gripping rolls rotatably mounted in each cradle and movable therewith, means for simultaneously oppositely pivoting said cradles to straighten said material in its passage through said rolls, and means for adjusting said supports to different widths of material including a reversely threaded screw, a bracket carried by said supports and movable with said screw and means for turning said screw.

7. A guiding and straightening mechanism for materials of the class described, comprising a frame, uprights and cross members, a pair of rotatable shafts supported on said uprights, spaced material guide supports on said cross members, a yoke carried by each of said supports, a pair of cradles pivoted in each of said yokes, a pair of material edge-gripping rolls rotatably mounted in each cradle and movable therewith, means for effecting the even passage of said material through said rolls, said means comprising a balanced feeler arm connected with said frame and fulcrumed midway of said rolls and through which said material is to pass, said feeler arm being adapted to be tilted by unbalanced forces exerted by the flow of the material as the material develops lateral movement, means operatively connecting said feeler arm and said shafts, and means transmitting motion from said rotating shaft to pivot simultaneously said cradles to alternately draw said material to right or left to straighten its flow through said rolls.

8. A guiding and straightening mechanism for materials of the class described, comprising a frame, uprights and cross members, a pair of rotatable shafts supported on said uprights, spaced material guide supports on said cross members, a yoke rigidly carried by each of said supports, a pair of cradles pivoted in each of said yokes, material edge-gripping rolls rotatably mounted in each cradle and movable therewith, means for effecting the even passage of said material through said rolls, said means comprising a balanced feeler arm connected with said frame and fulcrumed midway of said rolls over which said material is to pass and adapted to be tilted by unbalanced forces exerted by the flow of the material, a beam adapted to oscillate with said feeler arm and having connecting rods operatively connected to each of said rotatable shafts to rotate the same, and means transmitting motion from said rotating shaft to pivot simultaneously said cradles to straighten its flow through said rolls.

9. A guiding and straightening mechanism for materials of the class described, comprising a frame including uprights and cross members, a pair of rotatable shafts supported on said uprights, spaced material guide supports on said cross members, a yoke rigidly carried by each of said supports, a pair of cradles pivoted in each of said yokes, material edge-gripping rolls rotatably mounted in each cradle and movable therewith, means for effecting the even passage of said material through said rolls, said means comprising a balanced feeler arm connected with said frame and fulcrumed midway of said rolls over which said material is to pass and adapted to be tilted

by the unbalanced forces resulting from the flow of material as it develops lateral movement, means limiting the tilting of said feeler arm in either direction, said means including a balance, a beam adapted to oscillate with said feeler arm and having connecting rods operatively connected to each of said rotatable shafts to rotate the same, and means transmitting motion from said rotating shafts to pivot simultaneously said cradles to straighten the material.

10. In a device of the class described, a frame including cross members, a pair of rolls to grip each margin of the material to be guided pivotally and slidably connected with said cross members, a feeler arm adapted to be balanced by straight flow of the material and unbalanced by lateral deviation thereof, and means actuated by said feeler arm including members adapted to produce simultaneous equal pivoting of each pair of said rolls whereby opposite force is exerted on each margin of the material.

11. A guiding and stretching mechanism of the class described comprising a frame including uprights and cross members, spaced material guide supports mounted on said cross members for lateral adjustment, a pair of rolls pivotally mounted in said supports for free rotation and disposed to exert equal pulls on each margin of the cloth, means disposed in the center of the path of the flow of the material adapted to be pivoted by the forces exerted by lateral deviation of the material, and a connection from said means to pivot said rolls oppositely but equally to increase the pull of the rolls on the side from which the material has retreated and to decrease the pull of the other pair of rolls whereby the proper flow of material is immediately restored.

12. In a device of the class described, a frame, a pair of material guides pivotally mounted on said frame, separate means for pivoting each of said guides, a balanced arm adapted to be tilted by lateral deviations of the material, and members connecting each of said guide pivoting means with said arm to actuate each of said guide pivoting means equally but oppositely.

13. In a device of the class described, a frame, a pair of material guides pivotally mounted on said frame, separate means for pivoting each of said guides, a balanced arm adapted to be tilted by lateral deviations of the material, said arm including a plurality of cross members to receive the material, and members connecting each of said means with said arm to actuate each of said means equally but oppositely.

14. In a device of the class described, a frame, a pair of cradles mounted on said frame adjacent the margins of the material, a pair of freely rotatable rolls mounted in each of said cradles to grip the margins of the material and disposed at an equal acute angle against the flow of the material to create an equal pull on each margin, a centrally pivoted feeler arm adapted to receive the correct flow of the material as a balanced load and to be tilted by lateral deviation thereof, and means operated by said arm as it tilts and adapted to pivot each of said cradles equally in opposite directions, whereby the angle of the rolls to the cloth becomes more acute on the side from which the material is retreating and the angle of the rollers on the other margin becomes less acute producing pulls of unequal force on the margins of the material to restore desired flow thereof.

15. In a device of the class described, a frame, a pair of guides pivotally mounted on said frame

and spaced to grip each margin of the material, a centrally pivoted arm adapted to receive the material in correct flow as a balanced load and to be tilted by lateral deviations thereof, a beam 5 movable with said arm, separate means for pivoting each of said guides, a pair of shafts, a rod from each end of said beam to one of said shafts and connected therewith to rotate said shaft in either direction and a connection between said 10 shaft and said guides adapted as said arm tilts to pivot said guides equally but oppositely.

16. In a device of the class described, a frame, a pair of guides pivotally mounted on said frame and spaced to grip each margin of the material, a 15 centrally pivoted arm adapted to receive the material in correct flow as a balanced load and to be tilted by lateral deviations thereof, a beam movable with said arm, a toothed member with each guide, separate means for pivoting each of 20 said guides, each of said means including a shaft, a gear on said shaft in mesh with said member, a second gear on said shaft, a rack in mesh with said second named gear, a pair of shafts, a rod from each end of said beam to one of said shafts

and connected therewith to rotate said shaft in either direction and connections between said shaft and said rack to raise or lower said rack as said arm tilts whereby said guides are pivoted equally but oppositely. 5

17. In a device of the class described, a frame, a pair of members slidably carried by said frame to permit adjustments for different widths of material, a pair of supports pivotally mounted in each of said members, a roll mounted for free 10 rotation in each of said supports and rolls in said pairs of supports constituting a grip for each edge of the material, and means for pivoting each pair of said rolls, said means including a toothed member with each support, a shaft, gears on said 15 shaft in mesh with said toothed members, a centrally pivoted feeler arm on said frame responsive to the forces exerted by the flow of the cloth, means connected with said feeler arm to produce simultaneous equal rotation of said shafts where- 20 by said pairs of rolls are pivoted equally, but oppositely, to correct undesired lateral movement of the material.

ROBERT DANIEL TACKABERRY.
